(57) CLAIM

The ornamental design for a “display bench”, as shown and described.

DESCRIPTION

FIG. 1 is a perspective view of a “display bench” showing my new design;

FIG. 2 is a front elevational view thereof, the rear elevational view being identical thereto;

FIG. 3 is a top plan view thereof;

FIG. 4 is a bottom plan view thereof;

FIG. 5 is a left side elevational view thereof, the right side being identical thereto; and,

FIG. 6 is a perspective view similar to FIG. 1 showing the “display bench” in use supporting horizontal surfaces.

The broken line showing of the horizontal surfaces is for environmental purposes only and forms no part of the claimed design.
